(57) **CLAIM**

The ornamental design for a digital dental mirror, as shown and described.

DESCRIPTION

FIG. 1 is a perspective view of a digital dental mirror showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof, showing the digital dental mirror in use, coupled to a power core; and,

FIG. 9 is a perspective view thereof, showing the mirror portion separated from the main body portion.

The broken lines illustrate environmental structure which forms no part of the claimed design. The dash-dot broken lines in FIG. 9 represent a boundary that forms no part of the claimed design.
